(57) **CLAIM**

The ornamental design for a container for liquid, as shown and described.

DESCRIPTION

FIG. 1 is a perspective view of a container for liquid showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is an enlarged top view thereof; and,

FIG. 8 is an enlarged bottom view thereof.

The broken lines shown in the figures depict portions of the container for liquid that form no part of the claimed design.
